UNITED STATES PATENT OFFICE

2,675,812

HEAD COVERING

Elaine Berg, Chicago, Ill.

Application February 7, 1952, Serial No. 270,481

1 Claim. (Cl. 132—49)

1

The present invention relates to head coverings, and is particularly concerned with the provision of an improved construction of non-creasing hairnet.

In beauty shops it is the practice to hold the hair in place after setting or waving with a hairnet, and hairnets are also worn by workers, the net being so applied that the elastic which extends about the periphery of the net engages the forehead of the wearer. This tends to produce an indentation or crease in the forehead of the wearer which detracts from the personal appearance of the user for a short time after the removal of the net.

One of the objects of the invention is the provision of an improved construction of non-creasing hairnet in which provision is made for the renewal of the hairnet so that when the hairnet has worn out it may be replaced by the user at a minimum amount of expense.

Another object of the invention is the provision of an improved non-creasing hairnet in which the assembly may be manufactured at a minimum amount of expense by unskilled labor and without necessity for permanently securing the parts of the assembly together by means of glue or other adhesive as has been done in the prior art.

Another object of the invention is the provision of an improved form of non-creasing hairnet in which the elastic which surrounds the periphery of the hairnet is permitted to expand and contract freely inside the forehead shield, and in which the shield is attached to the hairnet by means of tabs passing through openings in the hairnet as distinguished from a rigid securing of the elastic in the devices of the prior art.

Another object of the invention is the provision of a plurality of forms of quickly detachable forehead shields for non-creasing hairnets, some of which may be maintained in constantly clean condition by merely wiping them off with a damp cloth, and others of which are provided with special means for absorbing perspiration and further enhancing the comfort of the shield.

Other objects and advantages of the invention will be apparent from the following description and the accompanying drawings, in which similar characters of reference indicate similar parts throughout the several views.

Referring to the single sheet of drawings accompanying this specification,

Fig. 1 is a front elevational view showing a user with a non-creasing hairnet embodying the invention;

2

Fig. 2 is a view in perspective of my improved non-creasing shield;

Fig. 3 is a plan view of the pattern of the shield of Fig. 2;

Fig. 4 is a fragmentary bottom edge view of that portion of the shield and net which is located adjacent the forehead, seen from the top of Fig. 1;

Fig. 5 is a fragmentary sectional view taken on the plane of the line 5—5 of Fig. 4, looking in the direction of the arrows, and showing the manner in which the tabs of the shield pass through and are secured to the hairnet;

Fig. 6 is a fragmentary, front elevational view of another modified form of shield and net which may be equipped with a sweat band;

Fig. 7 is a transverse sectional view taken on the plane of the line 7—7 of Fig. 6, looking in the direction of the arrows.

10 Referring to Fig. 1, 10 indicates in its entirety the non-creasing hairnet assembly which includes a shield 11 and a net 12.

15 The hairnet comprises a reticulated body 13, the periphery of which is provided with an elastic band 14, about which the body may be folded or the elastic band may extend in and out of the holes of the net adjacent the edge thereof.

20 The present invention is applicable to all types of hairnets and may be applied to any hairnet purchased on the open market.

25 The shield 11 is preferably made of relatively stiff sheet material, such as a fabric of filled buckram, which may be purchased in many different colors and may, therefore, harmonize in color with the color of the net or the hair of the user.

30 The buckram sheet material retains its crease or fold 15, when it is bent backward upon itself to form a U-shaped member, having the two layers 16 and 17 which form the body of the shield.

35 The body of the shield 11 is preferably substantially rectangular in shape except that one of the layers 16, that is the outer layer, is provided with longitudinally extending rectangular tabs 18 and 19, projecting centrally from each end.

40 The tabs are in alignment with the ends of a pair of slits 20, 21, which are formed in the other layer 17, the slits extending parallel to the end edges 22, 23 of the rear layer 17.

45 In order to attach the shield to the hairnet, the shield is folded substantially as shown in Fig. 2, and the edge of the hairnet 12, with its elastic 14, is placed in the trough 24, formed by the shield, and moved down into the groove at the crease 15.

Without necessarily stretching the elastic, the net itself has its body extended inside the trough 24 to its full length, and thereafter the tabs 18 and 19 are passed through the adjacent apertures in the net body, such as, for example, the net aperture 25, Fig. 5.

The tabs 18 are then folded over to U-shape and their ends are extended through the slits 20 and 21 and pushed in tightly until the tabs form a U-bend at 26 and 27, where they emerge from the apertures of the net body; and the inner ends 28 and 29 of the tabs are effectively confined between the two layers 16 and 17 of the shield.

Thus the body of the net is removably attached to the shield without affecting the extension or contraction of the elastic band 14, which extends about the periphery of the net.

Whenever the net wears out a new net may be installed in its place, or if a different color or kind of net is desired, it may be readily replaced.

It will thus be observed that I have invented an improved non-creasing hairnet in which the hairnets are constantly renewable and in which the extension and contraction of the elastic is unhampered by the attachment of the shield to the body of the net.

The present assembly may be made with a minimum amount of labor and material, and may be attached to the hairnets by unskilled labor. Neither is it necessary to delay the packing of the hairnets until the adhesive has dried, and nets which have been assembled with shields may be immediately stacked and packed in a single operation.

Referring to Figs. 6 and 7, these are views of another modified form of detachable shield for preventing creasing by a hairnet. In this case the shield 31 comprises a relatively stiff yet bendable sheet of transparent, shiny, smooth plastic which is of substantially rectangular form but is provided with rounded ends.

The transparent plastic sheet may in some cases be used alone and secured to the front of the hairnet as described hereinafter, in which case it might be substantially invisible, if transparent. In the embodiment of Figs. 6 and 7 the sheet 33 has secured to it a rear layer of felt 34, by means of adhesive for serving as a sweat band.

The felt 34 and the plastic 33 are coextensive and both are provided adjacent each rounded end with a concentric hole 35. In each case a slit 36 is made from the hole 35 to the end in both the plastic and the felt, and the slit 36 provides a closable form of entry into the hole 35.

The net is attached by passing one of the tabs upon the adjacent side of the slit 36 through a hole in the net, and the body of the net is then drawn tightly longitudinally of the shield 31 and the corresponding tab on the other end is passed through to the hole in the net. The elastic which surrounds the periphery of the net

is left free to expand and contract along the shield and through the holes.

In this case the shield is not folded but lies flatly against the forehead behind the forward edge of the net and protects the forehead against creasing by the net and absorbs perspiration.

Like the other shield, this one is quickly detachable and whenever a net has worn out it may be replaced, and the present shield is particularly appropriate for using under a drier because it absorbs the perspiration from the forehead.

While I have illustrated a preferred embodiment of my invention, many modifications may be made without departing from the spirit of the invention, and I do not wish to be limited to the precise details of construction set forth, but desire to avail myself of all changes within the scope of the appended claim.

Having thus described my invention, what I claim as new and desire to secure by Letters Patent of the United States, is:

A noncreasing hairnet assembly comprising a hairnet of reticulated hairnet material, having a multiplicity of apertures, and having an elastic band extending about its periphery, a removable forehead shield comprising a strip of relatively stiff sheet material folded backward upon itself to form a trough defined by two portions of equal width for receiving the edge of the hairnet, and provided at each of its ends with an outwardly extending tab of sufficient size to pass through apertures in the body of the hairnet, said tabs extending from one of said portions, the other of said portions being provided adjacent its ends with a pair of slits of sufficient length to pass said tabs when they are folded back endwise, the said tabs securing the shield to the hairnet and holding the hairnet between the parts of the shield without hampering the extension or contraction of said elastic band, the said tabs passing through apertures in the hairnet and being bent backward at the ends of the portions supporting said tabs, and being passed inward through the said slits in the body of said shield to hold the tabs in substantially parallel position with respect to the shield, the shield being arranged with the tabs inwardly and the unslit portion of the shield outwardly.
